HEAT TRANSFER DEVICE FOR
CORRUGATOR ROLLS

Henry B. Greenwood, Glen Arm, Md., assignor to
F. X. Hooper Company, Inc., Glen Arm, Md.,
a corporation of Maryland

Application December 29, 1937, Serial No. 182,229

1 Claim. (Cl. 257—95)

The invention relates to the production of corrugated paper and corrugated board of the single and double-faced variety.

In the production of corrugated paper, which may either be sold for use in this form or provided with a flat facing sheet on one or both sides, it is regarded as essential to heat the corrugator rolls between which the "straw", as the cheap paper that is treated in this way is called, is passed in the corrugating operation; and it is to the heating of these rolls that the invention primarily relates, though it is capable of application to other rolls used in presenting the facing sheets or webs and in the application of the same.

The prior art and the existing practice include the heating of the corrugator rolls, as above outlined, by means of steam introduced continuously during the operation of the rolls in any suitable manner, the usual practice being to make the rolls hollow or tubular and introduce the steam to the chamber or hollow within the roll, and to discharge the condensed water therefrom by means of pipes or tubes arranged concentrically with the axis of the roll.

In the heating of the rolls by steam there is a considerable degree of condensation due to the abstraction of heat from the rolls incident to heating the paper or straw web and also due to the exposure of the heated rolls to the air. The condensed water which results from this action presents a considerable obstacle to the efficient heating of the cylindrical walls of the rolls and particularly to their outer surfaces where they contact the paper or straw. This obstacle is in the nature of an insulating effect due to the fact that the condensed water forms a film of greater or less thickness on the inner surface of the roll, which cannot be eliminated by the usual methods of removing condensed water, the known tendency of the water being to distribute itself by centrifugal action and the action of gravity over the entire inner surface of the roll which, in the absence of this film, would be in direct contact with the hot steam. The insulation thus accomplished is highly detrimental to the efficient transfer of heat from the steam in the chamber to the paper.

An object of the present invention is to provide heating surfaces or heat-absorbing surfaces in heat-conducting relation to the outer walls of the rolls, which heat-conducting surfaces are so arranged as to be substantially free at all times from this film or coating of condensed water and in direct contact with the steam, thus giving added efficiency in the transfer of the heat from the steam content of the chambers within the rolls

to the outer surfaces of the rolls and hence to the paper.

It is also an object of the invention to arrange these heating or heat-absorbing surfaces so as to prevent coating with a film of water. For this purpose they are arranged inwardly from; i. e., nearer the axis than, a point of accumulation of the condensed water. Such heating or heat-absorbing surfaces are most conveniently located on fins or vanes inside the roll and connected in heat-transferring relation to the wall of the roll.

The invention also contemplates the provision in combination with heating or heat-absorbing fins of means for confining the condensed water to a limited area to prevent the formation of a film of water on the fins. The corrugator rolls have been provided previously with means for discharging condensed water. In order not to interfere with this operation the fins are, in the preferred form, arranged in a helix or are otherwise helically inclined to the roll axis to cooperate with the discharge means. It is feasible, however, to effect a different arrangement of these fins whereby they are entirely independent of any means for collecting the condensed water or its removal.

In each instance, there is means for discharging condensed water and preferably a reservoir for the same below the main fin surface area. The fins, on account of their radial extent from the bottom of said reservoirs, are free of any water film and are exposed to direct contact with and to the full heating action of the steam; and these fins, being directly attached to the cylindrical outside walls of the rolls, conduct the heat from the steam directly to these walls from whence it passes to the outer surface which contacts the paper or straw. These fins and reservoirs may be in any desired arrangement and combined with any suitable means for discharging the condensed water.

In the drawings:

Figure 1 is a longitudinal fragmentary section through a single-facer type of corrugating machine, showing the conventional arrangement of corrugating and facer rolls.

Figure 2 is a side elevation of a heated corrugator roll together with the steam supply and the discharge means for the condensed water, the roll being broken away intermediately to show the same in longitudinal section on a plane of the roll axis.

Figure 3 is an enlarged section taken on the line 3—3 in Figure 2.

Figure 4 is a fragmentary section on the same

plane as Figure 2 showing a corrugator roll equipped with another form of heat-transfer fin or vane.

Figure 5 is a section similar to Figure 4, showing still another form of heat-conducting vane or fin.

Figure 6 is a section on a reduced scale corresponding to Figure 2, showing a roll equipped with a heating fin or vane differently arranged.

10 Figure 7 is a section on the line 7—7 in Figure 6.

Referring to the drawings by numerals, each of which is used to indicate the same or similar parts in the different figures, the construction shown in 15 Figure 1 comprises a side frame 1 on the far side of the machine. It also includes upper corrugator roll 2, lower corrugator roll 3, presser roll 4 for applying the facing web to the corrugated web, paste rolls 5 and 6, paste trough 7, and facing web, heating and transmitting rolls 8 and 9.

The corrugator rolls 2 and 3 are grooved longitudinally at 10 in accordance with the usual practice, and the corrugations of these rolls are meshed at 11 so that the straw web 12, which is 20 fed to the top of the upper roll 2 and passed around the same downwardly in right-handed rotation and rearwardly between the rolls at 11, is distorted and pressed in the form of corrugations at this point and, passing around the roll 3 in 25 left-handed rotation, is paste-coated by means of the upper pasting roller 5, the facing web 14 being applied at the contact zone of the rolls 3—4 indicated by reference character 15, the finished single-faced web being indicated at 16 and it 30 being understood that the roll-heating device of the invention may, if desired, also be employed in connection with rolls for applying the second facing web or sheet in the production of double-faced corrugator board. All said rolls are, in accordance with existing practice, made hollow and 35 are steam heated.

The facing web 14 which is fed from the right at the bottom of the construction shown in Figure 1 in any suitable manner is passed clockwise 40 to the left and upwardly substantially half way about the heating and transmitting roll 9 and upwardly to the second heating and transmitting roll 8, passing about the right of the same in left-handed rotation, being passed from the top of this 45 roll to the bottom of pressing roll 4, and being passed upwardly and clockwise about this roll to the contact point 15 where the operation of affixing the facing sheet or web to the corrugated paper takes place as already described.

50 Figure 2 shows a corrugator roll A grooved or corrugated exteriorly in the usual manner at 10 and having a shaft 16 secured to the roll at its right-hand end, which shaft is mounted in suitable bearings 17 to rotate therein. At its 55 opposite end, the roll has a hollow shaft 18 secured thereto in any suitable manner and mounted to rotate in bearings 19, both sets of bearings being supported on the side frames 1 and 1'.

55 The passage or opening 20 within the shaft is connected at 21 to the chamber 22 within the roll A, which represents the corrugator roll construction 2 or 3, Figure 1, to which chamber 22 steam is fed by way of the passage 20 from 60 a conventional steam joint 24 provided for this purpose and fed by a steam pipe 25 which carries live steam to chamber 23 in said fitting, which chamber is connected to the passage 20. The steam joint 24 is also provided with a condensed water discharge chamber 26 to which a

downwardly disposed discharge pipe 27 is connected, and this condensed water discharge chamber 26 is connected to chamber 22 within the roll by a pipe 28 which extends through the passage 20 within the shaft 18 and is turned downwardly within the roll, having its intake opening 29 near the bottom of a circular peripheral groove 30 which is shown as near the end of the chamber 22 at the left in Figure 2; i. e., toward the bearing 19, and side frame 1'. The condensed water may be removed by siphonic action or any suitable type of suction device, this particular arrangement for introducing steam and discharging condensed water by way of the axis of the roll, being known to the art. 15

An important feature of the invention resides in the provision of the fins or vanes 31 which project inwardly from the wall surface 33' of the roll and of chamber 22 in a radial direction 20 toward the axis of the roll, providing between them a deep storage reservoir 32 for condensed water which leaves the vanes or ribs 31 exposed at all times and free of any water film, the storage chamber 32 between the ribs being of 25 sufficient volume to accommodate the condensed water in contact with the wall surface 33' of the roll at the bottom of reservoir 32, leaving at least four-fifths of the height or depth of the fins or vanes 31 exposed to direct contact with 30 the steam, whereby they serve as conductors for leading the heat abstracted directly from the steam to the outer surface of the roll at 33.

In the form shown, though other arrangement is contemplated, the storage chamber or 35 reservoir 32, being in the form of a helically arranged channel between the ribs or vanes 31, serves to conduct the condensed water to the circular peripheral groove 30 where it is taken up by the discharge pipe 28 at the depending intake end of the same at 29, the helix being suitably related to the direction of rotation for this purpose. The radius or depth of groove 30 is 40 preferably a little greater than the radius of the remainder of the chamber 22. 45

Figure 4 shows the fins or ribs 31' extended and increased as to their heat-absorbing surfaces by means of suitably arranged plates 34 seated in slots 35 located in the inner faces 36 of the ribs or vanes 31'. These plates are shown as extending helically about the axis along the inside of the roll. The drawing shows a securing means in the form of solder or other strip of metal 37 forced or otherwise inserted in the groove 35 at the side of the base portion of the 50 plate 34. This form also includes storage reservoir 32 which accommodates the condensed water, holding it out of contact with the main portion of the vane surface area, the water occupying but a small volume at the bottom of its 55 reservoir 32.

Figure 5 shows a heat-absorbing fin or vane 31'' having its inwardly-disposed surface 39 inclined to the axis, forming sharp edges 40, thus eliminating any possibility that the condensed 60 water may form a film on the inner surfaces of the ribs, the corresponding surfaces being indicated at 39' in Figure 2. The inclined surface 39 provides for the projection outwardly into the bottoms 33' of the grooves or reservoirs 32 of any 65 water which may be deposited on the surfaces 39, thus leaving the entire rib under all circumstances, except for the slight area which may be immersed at the base, fully exposed to heating by the action of the steam, giving a consequently 70 75

more efficient transfer of the heat to portions 40 of the ribs and thence to the surfaces 33 of the rolls. This shaping of the ribs as distinguished from that in Figure 2 is a refinement giving increased exposed surface as well as slightly better clearance of water.

Figures 6 and 7 illustrate still another type of heating device in the form of longitudinally-arranged ribs or fins 45, as best shown in Figure 7. The inner surface 46 of the wall 47 of the roll is provided with shallow peripheral grooves 48 which are connected together by longitudinal grooves 48', which also connect grooves 48 to a relatively deep peripheral groove 49 at the end of the roll or otherwise suitably located from which the condensed water is removed by means of a pipe 28, 29 by siphoning or otherwise, as in Figure 2. The vanes 45 span the grooves 48 and do not obstruct them but deflect the water into the grooves 48 and 48' the over-flow being deflected to the discharge groove 49 and removed. The fins 45 can be combined with any means for collecting and discharging the water, their main purpose being to provide a heat-absorbing surface which is not film-coated, and thus serve to abstract the heat directly from the steam. The fins 45, as shown, are freed of any film of condensed water by centrifugal action; and, being in close contact with the inner surface 46 of the outer wall 47 of the roll, they receive the heat from the steam and transmit it with high efficiency to this wall through which it is conducted directly to the outer surface of the roll, and thus applied to the paper.

The heating device of the invention is capable of application to any and all of the hollow rolls for making corrugated board according to the practice outlined.

The important feature of the invention resides in the provision, on the inside of a hollow steam-heated roll of a corrugating machine, of fins which are directly connected in heat-exchanging relation with the outer wall of the roll and project inwardly toward the axis of the roll from the outer wall surface thereof, the roll also being equipped with means for disposing of the condensed water and leading it from the chamber within the roll, whereby only a small quantity of water is normally retained within the roll and this is displaced outwardly from the axis of the roll by the action of centrifugal force, adhesion, and gravity and preferably in a suitable reservoir in the form of one or more depressions in the inner surface of the outer wall of the roll, whereby

substantially the entire surface of the fin or fins is free of any water film which might tend to form on the inner surface of the roll as previously constructed. In this way the fins are exposed to the direct heating action of the steam and serve to conduct the heat to the main portions of the walls and to the outer surface of the roll by which it is applied to the paper.

While it is found most convenient from a practical and economical standpoint in making the rolls to give the fins a helical arrangement as shown in Figures 2, 4, and 5, they can be otherwise arranged with almost equal efficiency by running the fins longitudinally or in other non-helical arrangement and providing grooves or other means independent of the fins for draining the inner surface of the roll. The fact that the drainage channel is between the fins in Figure 2 is purely incidental to convenience of arrangement, but this does not interfere with the satisfactory transfer of heat from the steam to the fins; the portion of the area between the fins which is actually occupied by condensed water being at the bases of the fins; i. e., the portion which is outermost in the direction of the radius, 25 and the portion of the fins which is normally exposed being at least four-fifths of their radial extent, as indicated by dotted lines W in Figure 2.

I have thus described a preferred and modified form of the invention, the description being specific and in detail in order that the manner of constructing, applying, operating, and using the same may be fully understood; however, the specific terms herein are used descriptively 35 rather than in a limiting sense, the scope of the invention being defined in the claim.

What I claim as new and desire to secure by Letters Patent is:

In a corrugator roll for making corrugated paper having a chamber within the roll and means for introducing steam into said chamber and discharging condensed water therefrom, thin sheet metal vanes in said chamber in heat-conducting relation with the outer surface of the roll 40 and projecting inwardly from the walls of said chamber toward the axis of said roll beyond the area adjacent to the outer walls of the chamber occupied by condensed water and in heat-exchanging relation with the steam in said 45 chamber to conduct heat from the steam within the roll chamber to the outer surface of the roll.

HENRY B. GREENWOOD.
